UNITED STATES PATENT OFFICE.

LESTER W. RADMAN, OF BUCKHANNON, WEST VIRGINIA.

TIME CONTROL SWITCH.

Application filed February 21, 1923. Serial No. 620,328.

To all whom it may concern:

Be it known that I, LESTER W. RADMAN, a citizen of the United States, residing at Buckhannon, in the county of Upshur and State of West Virginia, have invented certain new and useful Improvements in Time Control Switches, of which the following is a specification.

My invention relates to improvements in time controlled switches, the primary object thereof residing in the provision of such a switch that may be readily associated with practically all types of alarm clocks, with which I am now familiar, the invention being further characterized by its simplicity of construction and ease of application to and removal from the said alarm clocks, the device constituting relatively few parts, and these correlated in such manner as to reduce the liability of derangement to a minimum.

A further object of my invention is the provision of such a time controlled switch that is primarily, but not specifically, adapted to be employed in conjunction with the lighting systems for the show windows of department stores and the like, the switch being well adapted to cut out these lights at a predetermined time.

With the above and other objects in view, the nature and advantages of my device will be readily understood by a careful review of the specification when considered in conjunction with the drawings.

In the drawings forming part of this application, like numerals of reference indicate similar parts in the several views, and wherein:

Figure 1 is a cross sectional view of my switch casing, the same being shown as applied to a conventional type of alarm clock, the switch mechanism being shown in side elevation.

Figure 2 is a rear elevational view of this casing disposed upon the clock.

Figure 3 is a cross sectional view of my improved switch.

Figure 4 is a rear elevational view of the switch, per se.

Figure 5 is a cross sectional view taken substantially upon the line 5—5 of Figure 3, and

Figure 6 is a perspective of one of the elements constituting my improved switch.

Referring to the drawings in detail, A designates an alarm clock of the usual construction, and B the casing for my switch mecha-

nism, which is preferably of square shape as shown and having in the front wall thereof, an opening b for the reception of the usual reduced portion a of said alarm clock, 60 this opening b being formed at its inner side with a flange c.

The reference character 5 indicates the alarm spring winding shaft of the clock, one end of this shaft being reduced and screw 65 threaded as at 16 for the reception of the usual finger winding member 7. In applying my switch to the type of alarm clock shown, the said finger winding member 7 is removed from the winding shaft of the 70 clock, at which time, my switch casing B may be positioned thereon in a manner more clearly indicated in Figure 1.

Within this casing is a square shaft 8, the front end of which is formed with a 75 screw threaded socket for receiving the said reduced and screw threaded end 6 of the clock spring shaft 5. Adjacent the front end of this shaft 8 is a porcelain insulating member 9, preferably round in shape, and having an opening 10 therethrough, which opening is centrally of the insulating block 9 and is also round-shaped to permit the said shaft 8 to rotate therein. The front face of this block 9 has close contact with the adjacent wall of the clock A, the opposite face of the block carrying a pair of diametrically disposed stationary contact arms 11, to which are secured the wires 12 of a lighting circuit.

Also upon the front face of the insulating block 9, and between the stationary contact arms 11 is a metallic disk 13, the same being also provided with a central opening, which is round shaped for permitting the said shaft 8 to rotate therein, this disk 13 being formed with lateral extensions 14 formed with openings therein, for the reception of set screws 15, whereby this disk may be rigidly secured to the block 9 and the casing A. 90

The disk 13 is further formed at diametrically opposite sides of the shaft 8 with a pair of arcuate slots 16 and carried by the shaft 8 and rotating therewith and in face to face contact with the disk 13 is a relatively smaller disk 17, the same being formed with a pair of laterally extending fingers 18 which are bent forwardly as at 19 and adapted for engagement within the said slots 16 of the first mentioned disk 13. Carried by the shaft 8 and insulated therefrom as at 20, in Figure 3, is a still further disk

21, the same being directly forwardly of the disk 17 and formed with contact arms 22, which arms are in direct alinement with the ends of the said stationary contact member 5 11 carried by the said insulating block 9.

Adjacent the outer end of the square shaft 8, the same is grooved as at 23 for the reception of a removable metallic plate 24 and between this plate 24 and the disk 21 carrying the contact arms 22 is a coiled spring 25 which tends to maintain the several disks in close contact with each other as well as maintaining the insulating block 9 in face to face contact with the adjacent wall of 15 the casing of the clock A.

The extreme end of this shaft 8 projects through an opening in the switch casing B, and is reduced and screw threaded as at 26 for receiving the said finger winding member 20 7.

The remaining control shafts of the alarm clock are also extended through the back wall of the switch casing B in any manner desirable, but preferably through the instrumentality of a shaft extension similar to the shaft 8, shown in several of the figures, and in the operation of my device, the alarm is set for a predetermined time, it being of course understood that previous to the application of my switch to an alarm clock the alarm spring is first wound to a certain degree, and after the switch has been applied to the clock, the key or finger member 7 may be rotated for engaging the movable 30 contacts 22 with the stationary contacts 11, at which time, the circuit will be completed through the wires 12. As soon as the alarm of the clock is unwound, the shaft 5 will rotate in a reverse direction for consequently 35 disengaging the movable contacts 22 from the stationary contacts 11 for thereby breaking the circuit to the wires 12.

In view of the above description when considered in conjunction with the drawings, it is believed by me that it will be readily appreciated by those skilled in the art, that I have provided a highly improved form of time controlled switch which is well adapted for application to practically all types of alarm clocks, and even though I have herein shown and described the preferred embodiment of the present invention, it is nevertheless to be understood that minor changes may be made therein, without departing 50 55 from the spirit and scope of the invention as claimed.

Having thus described my invention, what I claim as new, and desire to secure by Letters Patent is:

60 1. A time control switch for attachment to an alarm clock including a casing formed for receiving a portion of said clock, a base member removably mounted on the rear wall of the clock having an opening therein in

line with the alarm spring winding shaft, 65 a shaft section extending through the opening in the base member and removably connected with the spring winding shaft at one end and projecting through an opening in the casing at the other end for removably 70 receiving a winding handle, a pair of contacts mounted on said base member at opposite sides of that said shaft section, a cam disc mounted on the base member having an opening receiving said shaft section, a cam member mounted for rotation with said shaft section and for cooperation with the cam of said cam disc, a contact member mounted for rotation with the shaft section having contact arms for engagement with the contacts on said base member for closing the circuit between said contacts, and resilient means mounted on the shaft section and engaging the contact member for normally forcing said contact member, and said cam member toward said base member for holding said contact member in position for cooperative circuit closing relation with the contacts on the base, and said cam member for cooperation with the cam disc. 80 85 90

2. A time controlled switch attachment for alarm clocks including a casing formed for receiving a portion of the clock, a base member for attachment to the rear wall of the clock having an opening in line with the spring winding shaft of the alarm mechanism, a shaft extension of square cross section removably secured at one end to the alarm winding shaft and projecting outwardly through an opening in the casing at the other end for removably receiving the winding handle, said shaft extending through the opening in said base member, a cam disc removably mounted on said base member having an opening in the central portion thereof receiving the extension shaft, a cam member slidably mounted on said extension shaft and rotatable therewith for cooperation with the cam disc for limiting the rotative movement of the shaft extension in one direction, a contact member having a sliding insulated connection with said extension shaft for rotation therewith and provided with contact arms extending from diametrically opposite sides thereof, a pair of contacts mounted on the base member for cooperation with the contact arm, a disc member mounted adjacent the outer end of said extension shaft, and a coil spring interposed between said disc member and contact member for normally forcing said contact member and cam disc toward the base member, whereby the contact arms are held in position for cooperation with the contacts on the base and the cam member is held for cooperation with the cam disc. 100 105 110 115 120 125

In testimony whereof I affix my signature.
LESTER W. RADMAN.
